UNITED STATES PATENT OFFICE.

EMMETT A. SAUNDERS, OF SOUTH BEND, INDIANA.

RUBBER OVERSHOE.

1,239,434.

Specification of Letters Patent. Patented Sept. 4, 1917.

Application filed January 16, 1917. Serial No. 142,734.

To all whom it may concern:

Be it known that I, EMMETT A. SAUNDERS, a citizen of the United States, residing at South Bend, in the county of St. Joseph and 5 State of Indiana, have invented certain new and useful Improvements in Rubber Over-shoes, of which the following is a specification.

My invention relates to rubber overshoes, 10 and has for its principal object to provide a construction of overshoe that will improve the holding or gripping qualities of the heel portion of the overshoe on the heel portion of the shoe on which it is worn.

15 To prevent the heel of the overshoe from slipping down in walking, various structural expedients have heretofore been adopted, all of which are accompanied by one or more objectionable characteristics or results. The 20 most common method is to form the overshoe with a sole that springs upwardly from the ball of the foot to the toe, as compared with its position when worn, whereby the distance from the toe to the upper end of the 25 heel is somewhat shorter before the overshoe is put on than when it is on the shoe of the wearer. By reason of this construction, when the overshoe is fitted on the leather shoe, the entire top of the overshoe is made 30 longer, that is, stretched out, and the heel of the overshoe is thus tightened up and firmly secured to the heel of the leather shoe. As stated, the sole of the overshoe is curved substantially on the arc of a circle, 35 while the sole of the leather shoe is more nearly straight or flat; and the straightening out of the sole of the overshoe creates this pull and thus holds the shoe in place. This strain over the top of the shoe, however, is a 40 strain, not only on the overshoe, which tends to shorten the life of the latter and is the cause of many ruptures and breaks in the uppers of the overshoes, but it is also strain, pressure, and bond upon the foot of the 45 wearer which often causes much discomfort. Many people regard this "drawing" as an inseparable feature of a rubber shoe, and the same forms one of the grounds of dislike against the wearing of rubber overshoes.

50 The only relief against this discomfort in overshoes made on this principle is to wear a shoe one or two sizes too long and amply wide, but such an overshoe will not stay on, and the heel portion particularly is continu-

ally dropping down under the flexing of the 55 foot of the wearer.

Another plan which has been employed for causing the heel of the overshoe to stick in place, is to construct the heel portion somewhat narrower than the heel of the 60 leather shoe and stiffen or reinforce the sides of the heel so as to produce a lateral wedging or clamping action on the heel of the leather shoe, producing sufficient friction for holding 65 purposes.

Another method of attaining this result is to depend upon building the sole of the overshoe "short", and wedging the sole of the leather shoe into such shorter overshoe. In this case there need not be any draft over the 70 top of the foot, but the holding on is done by a draft from the toe of the rubber, nevertheless, due to the use of a heavy non-extensible cord that is carried around the toe of the overshoe substantially coincident with 75 the margin of the sole between the toe and the instep, and is then carried up from the instep to the back of the heel.

Still another method which has been proposed is to employ an integral band or rib 80 on the outer sides of the heel extending between the arch and the upper rear portion of the heel. This method is ineffective unless the heel itself be made so short as to be stretched when the overshoe is put on; and if this is the case, the outside rib or band is unnecessary and adds practically nothing to the holding-on quality of the overshoe. Given an overshoe that will drop off from 85 the heel, it is impossible to keep that overshoe on by the constricting pressure of an external rib, band, stay, or other like reinforcing device, for the obvious reason that a constricting pressure cannot be had without a previous expansion, and an external rib 90 or band, whether elastic or inelastic, cannot constrict or tend to constrict beyond its "point of ease" which is the dimension of 95 the overshoe on which it is formed.

All of these methods have their advantages and disadvantages, which are all well known, but none of them are perfect, and there is much room for improvement.

My present invention is based upon a holding principle that differs from all the 105 foregoing, and consists, broadly stated, in incorporating in the shoe an integral holding or gripping device that is located on, and

protrudes inwardly from, the inner surfaces of the sides of the heel, and extends in the general direction of a line connecting the upper rear portion of the heel and the arch. 5 This holding or gripping device may be a continuous member extending around the inner rear surface of the heel and obliquely down the sides thereof to or toward the arch of the sole, or it may consist of a pair of inwardly protruding ribs or bands on the inner surfaces of the sides of the heel, respectively, having this generally oblique direction of extension and of any suitable or desired length. In point of width, the holding or gripping device may be relatively narrow, or of considerable width, according to the kind of overshoe in which it is embodied, or the individual preference of the manufacturer.

20 This holding or gripping device, in any of the forms above suggested, constitutes in effect a holding band that hugs or embraces what may be called the "waist" of the heel. The line that defines this waist runs from the arch or "hollow" of the foot diagonally upward and around the heel through a point at the rear of the foot just below and back of an ankle joint. The location of this line is indicated in Figure 3 of the accompanying drawings by the median line of the rib 14.

Every shoe over which an overshoe is worn has the waist in this region, and I have discovered that if the overshoe be equipped with an internal band, rib, or thickened portion which occupies wholly or in part this section and protrudes inwardly from the general plane of the inner surface, the holding or gripping effect of the heel of the overshoe upon the heel of the leather shoe 35 may be so secured independently of all the other known methods hereinbefore alluded to, leaving the fore part of the overshoe entirely free, and without requiring either undue shortening of the overshoe to secure 40 the holding effect or undue lengthening of the same to secure comfort, or any narrowing of the heel portion, or any upward curving of the sole portion to produce a line of pull in the upper region of the overshoe.

50 In order that my present improvement may be readily understood by those skilled in the art, I have illustrated in the accompanying drawings several practical and workable forms in which the same may be embodied, and referring thereto—

Fig. 1 is a profile view of a last for a rubber overshoe, showing a groove in the waist portion of the heel designed to facilitate the manufacture of my improved overshoe; the 60 position of the latter on the last being indicated in the dotted lines.

Fig. 2 is a vertical transverse section of the overshoe on the line 2—2 of Fig. 3.

Fig. 3 is a vertical longitudinal section 65 on the line 3—3 of Fig. 2.

Fig. 4 is a sectional detail on the line 4—4 of Fig. 3, showing the holding rib or band protruding through a slit in the lining of the overshoe.

Figs. 5, 6 and 7 are views similar to Fig. 3, illustrating optional forms of the holding or gripping device of the overshoe.

Referring first to Figs. 2 and 3, 10 designates the upper and 11 the sole of a rubber overshoe. Extending between the upper rear portion of the heel designated by 12 and the arch designated by 13 is a rib 14 that is located on, and protrudes inwardly from, the inner surface of the heel portion of the upper, and occupies the "waist" region of the heel above referred to. This rib or band may conveniently be formed on the overshoe by means of a last such as is shown at 15 in Fig. 1, which is provided with a groove 16 occupying the same relative position as the rib 14. A reinforcing strip of raw rubber or other material suitable to form the rib 14 is pressed into the groove. The upper of the overshoe is then built upon the last, and when the shoe is vulcanized the strip lying in the groove becomes an integral or autogenous rib on the inner surface of the waist line of the heel. Rubber overshoes are commonly provided with a fabric lining, as indicated at 17 in Fig. 4. In such cases I preferably cut a slit in this lining on the section covering the groove or depression in the last, cover the last with the lining, and then apply the reinforcing strip on the outside of the lining, but pushing it through the slit in the lining down into the groove, so that when the finished shoe comes off the last that section of the strip which filled the groove will protrude through the lining and into the inside of the shoe in the manner illustrated in Fig. 4. This feature, however, is a structural detail, preferably employed, but not essential to the invention.

In Fig. 5 I have illustrated a holding or gripping device in the form of an inwardly protruding rib 18 that extends across the rear wall of the heel and down both sides, but stops some distance short of the arch, the lower ends 18' of the rib being preferably tapered down flush with the inner surfaces of the sides of the heel.

In Fig. 6 I have illustrated another modification of the holding or gripping means, consisting of an inwardly protruding rib 19 on each side wall of the heel, this rib stopping short of both the arch and the upper rear end of the heel, and preferably having both ends 19' tapered down flush with the inner surface of the side of the heel.

In Fig. 7 I have illustrated a still further modification of the holding or gripping device, consisting of a much wider internal protuberance 20 located as shown and described at 14 in Figs. 2 and 3. Obviously 130

this member 20 may have the same characteristics as to length as the rib 18 of Fig. 5 or the rib sections 19 of Fig. 6, if desired.

In all of the forms shown, assuming that the inner surface of the overshoe has a proper fit on the shoe over which it is worn, it will be manifest that the insertion of the heel of the shoe into the heel of the overshoe creates a stretching or expansion of the internal rib or rib sections, which latter react with a constricting pressure at the waist line of the heel, holding the latter securely on the heel of the shoe. It will be equally manifest that where such a rib or band is applied on the outside of the heel, unless the overshoe is built short relatively to the shoe on which it is worn, there can be no such constricting pressure of the rib or band, because there is no stretching or expansion thereof when the heel of the shoe is in the heel of the overshoe.

Different degrees of elasticity may be preferred by different overshoe makers, and for different overshoes by the same maker, and all may be used without going outside the principle of the invention.

It is believed that the foregoing description, taken in connection with the sample forms of the invention illustrated in the drawing, will make clear to those skilled in the art the nature, general structural features, and merits and advantages of the invention; and hence, without at all limiting myself to the particular embodiments herein shown and described, but reserving all such

variations and modifications as fairly fall within the spirit and purview of the invention,

I claim—

1. A rubber overshoe having incorporated therein integral relatively thickened elastic portions protruding inwardly from the inner surfaces of the sides of the heel and extending in the general direction of a line connecting the upper rear portion of the heel and the arch, said thickened portions adapted to be distended by insertion of the heel of the shoe into the heel of the overshoe.

2. A rubber overshoe having incorporated therein integral oblique elastic holding ribs or bands protruding inwardly from the inner surfaces of the sides of the heel, said ribs or bands lying between the upper portion of the heel and the arch and adapted to be stretched lengthwise by insertion of the heel of the shoe into the heel of the overshoe.

3. A rubber overshoe having incorporated therein elastic holding ribs or bands integral with and protruding inwardly from the inner surfaces of the sides of the heel, said ribs or bands extending longitudinally in the general direction of a line connecting the upper rear portion of the heel and the arch and lying in the waist region of the heel and adapted to be stretched lengthwise by insertion of the heel of the shoe into the heel of the overshoe.

EMMETT A. SAUNDERS.
